MACHINE FOR REFINING PAPER STOCK

William V. Knoll, Dayton, Ohio, assignor to Mid-West-Fulton Machine Company, Dayton, Ohio

Application July 8, 1936, Serial No. 89,586

3 Claims. (Cl. 92—24)

This invention relates to improvements in paper stock refining apparatus and particularly to apparatus including a beater engine. It embodies some of the principles employed in my Patent No. 5 2,061,622 of Nov. 24, 1936.

Apparatus of this kind usually comprises a beater engine with a storage and conveying trough for receiving the beaten stock from the beater outlet and returning it to the inlet for further beating.

These commercial beater engines usually comprise a large bladed roll of great weight, the blades of which rotate in proximity to the bladed bedplate over which the stock passes. Adjustment is provided for letting the roll downward toward the bedplate to compensate for wear, but there is nothing except the weight of the roll to prevent it from moving upward.

The number of cutting blades which may be employed in the bedplate, and consequently the disintegrating capacity of a beater of this type is therefore limited by the ability of the roll, due to its weight, to keep its blades in substantial contact with the blades of the bedplate. The result is that when a bedplate having a relatively large number of cutting blades is employed, the roll which will, in operation, remain in substantial contact with the bedplate is exceedingly heavy, consuming a large amount of power to merely overcome its resistance to rotation.

In refining apparatus of the aforesaid character the beater engine must not only serve the purpose of cutting and disintegrating the stock but must serve also as a pumping means capable of raising the beaten stock over a relatively high backfall, thereby to provide a sufficient head to cause the stock to move away from the beater outlet through the storage and conveying trough back to the inlet. Inasmuch as a beater engine, 40 properly constructed to be efficient as such, is highly inefficient as a pumping means for raising a fluid to a higher level a large amount of power is thus wasted.

Another disadvantage, in apparatus of this kind, is that the stock returns to the beater inlet and is brought into contact with the revolving beater roll at substantially no pressure, the result being that the spaces between the roll blades do not fill except when the roll is revolved at a slow 50 inefficient speed. Furthermore, the stock in contact with the roll at the beater inlet is under substantially zero velocity until brought into motion by the roll itself. The result is that each time a volume of the material enters the space 55 between two blades of the roll, this volume must

be raised almost instantly from a state of rest to the peripheral speed of the roll. Except in cases where engines of this class are revolved at a slow inefficient speed, the power consumed in thus overcoming the inertia of the material at the inlet is extremely high.

It has, however, been heretofore proposed to employ, in combination with a tank and beater engine, a separate pump for circulating the fluid mass through the system, these efforts having mainly for their object the provision of means to relieve the beater engine of the burden of discharging the stock over the relatively high backfall, which at the best provides a very small head, and providing instead a greater fall capable of moving the beaten stock away from the beater outlet more rapidly.

In my U. S. Patent No. 1,793,095 of February 17, 1931, the apparatus shown contemplates, among other features, the use of a small high speed beater roll and a separate pump, the pump being arranged not only to relieve the beater of the burden of raising the fluid mass over a backfall, but also to deliver it to the beater inlet under pressure, the object being to cause the pressure so applied to more thoroughly fill the pockets between adjacent blades of the roll even when the roll is being operated at exceptionally high speed and thereby to increase the capacity of the beater engine.

But while thus delivering the stock under pressure to the beater inlet has its advantages over common practice in more completely filling the spaces between the blades of a roll operating at high speed, thereby enabling a smaller roll to disintegrate a greater amount of stock in a given time, it will be found that a considerable portion of this gain is again lost due to the fact that the pressure is radially applied to the beater roll, and to that extent results in greater unit pressure being applied to the roll bearings creating higher friction losses, this effect being, of course, greater as the pressure at the inlet is made higher.

Furthermore, in my U. S. Patent No. 1,793,095, no provision was made or contemplated to insure that the incoming material shall be moving at a velocity substantially equal to the peripheral speed of the roll before it is permitted to come in contact with, and enter into the spaces between the roll blades.

Now the prime consideration in the design of a beater roll is its capacity to cut and disintegrate the fibrous material, whereas its ability as a pump to move the fluid, and as an engine capable of being acted upon by the fluid is necessarily

of secondary importance. But while the beater roll of common practice, as employed to raise the material over the backfall to a higher head is highly inefficient as a pump, using power for this purpose out of all proportion to the head created, this type of roll when designed with full consideration of its disintegrating capacity has been found to be relatively efficient as a turbine wheel when fluid under velocity has been applied thereto.

Systems employing this turbine principle have been proposed in several instances, yet in none of them have structures been provided which have their disintegrating and turbine elements arranged in a relation to each other which gives best results.

It is therefore an object of this invention to greatly increase the capacity of a stock refining unit of a given size, by providing a beater engine having a power driven roll with means extraneous to the beater roll for delivering the stock through the beater inlet to the periphery of the roll at high velocity, and causing it to impinge on the roll blades substantially tangential thereto after the manner of a turbine, and at a point immediately adjacent the bedplate, the speed of the stock being preferably at least equal to the peripheral speed at which the roll is being power driven, to the end that the stock, which for efficient operation must necessarily move through the beater at great speed, will, in doing so, preferably relieve the power means of as much driving effort as would otherwise be consumed in the circulating function, and further, by including means not dependent on rotation of the beater roll to move the stock away from the beater outlet so as to relieve the beater roll of the burden of raising the stock over a backfall to a higher level, whereby the power applied to the beater roll shaft is such only as is required for cutting and disintegrating the material.

In the apparatus disclosed in my Patent No. 2,061,662 of Nov. 24, 1936, the nozzle opening which was provided for converting the pressure, which the stock was under, into velocity, and directing it tangentially against the roll, was horizontally as wide as the roll, but vertically as narrow as the stock being delivered to the apparatus was capable of passing through without clogging. This was the limiting factor of the structure.

It is therefore a further object to provide, in the apparatus herein disclosed, nozzle construction which will convert a given pressure to a still higher velocity and direct it against the roll blades in the most effective manner, to the end that a still further saving in power consumption may be effected.

That these and other objects and meritorious features of the invention are attained will become apparent upon consideration of the description, reference being had to the drawings, wherein,

Fig. 1 is a plan view of the stock refining apparatus.

Fig. 2 is a side elevation.

Fig. 3 is a rear end elevation.

Fig. 4 is an enlarged fragmentary section through the nozzle structure taken at 4—4 of Fig. 5.

Fig. 5 is a still further enlarged fragmentary view thru the nozzle structure taken at 5—5 of Figs. 1 and 4.

Similar numerals refer to similar parts thruout the several views.

Referring now to the drawings, the beater engine, which may be broadly designated by the numeral 10, comprises a roll 11 supported by the shaft 12 rotatable in bearings 14. The bearings 14 are held in bearing blocks 16 vertically slidable in the end frames 18. Threaded rods 20 are non-rotatably secured in the tops of the blocks 16 and extend through threaded openings in worm wheels contained within the gear casing 22. The worm wheels are rotatable by worms within the 10 casing operable by the shaft 24 whereby the roll may be raised or lowered and held positively in any position to which it may be moved.

On the periphery of the roll 11 are a plurality of blades 26, spaced to form pockets 27, and secured in the bedplate 28 are the bedplate bars 30, the ends of the bars being held by the plate close to the ends of the roll blades in the usual manner.

The forward end of the inlet housing 32 is secured to the roll housing by the flange 34, the rearward end thereof being secured to the supply pipe 36 by the flange 38. The inside of the inlet housing tapers sharply from the flange 38 toward the flange 34 thereby providing the narrow passage 40 through which the stock is discharged against the roll blades.

In my Patent No. 2,061,662 of Nov. 24, 1936, the narrow discharge nozzle is in the form of a slot, the horizontal dimension of which is substantially the width of the roll and the vertical or narrow dimension is substantially the radial depth of one of the spaces between two roll blades. But while lessening the vertical dimension of the nozzle slot was found to increase the 35 nozzle velocity of the material, the capacity of the nozzle to pass lumps in the stock passing through, became, of course, proportionally less.

In the structure herein disclosed, the vertical dimension of the nozzle is made somewhat greater, and the opening is then divided by a series of tapering partitions 42, thereby dividing the main nozzle, near its end, into a series of separate openings 44 between the partitions, the combined width of these openings being, in the 45 structure shown, somewhat less than half the width of the roll. With this structure it was found that, although the vertical or smallest dimension of the opening was greater, and for that reason greater lumps could be passed through 50 the nozzle, the discharge velocity was greatly increased.

The openings 44 are shown square, tapering toward the outlet both in their vertical and horizontal dimensions. It will be evident, however, 55 that round tapering openings or openings or any other suitable shape may be employed. It is important, however, that the ends of the nozzle openings be far enough from the roll blades to allow the stock to spread laterally, that is, in a 60 direction lengthwise of the roll, before it reaches a position between the roll blades at the first bedplate bar, as otherwise the spaces between the blades would be filled only at points in line with the openings 44 thus leaving points in line 65 with the partitions 42 unfilled.

In order to further facilitate the spread of the stock laterally, after it leaves the ends of the nozzle openings 44, the spreading plate 46 is provided. This plate curves slightly upward at 70 the edge 48 until this edge is substantially in line with the center of a nozzle opening 44 which naturally lessens the vertical dimensions of the streams when they strike it.

The lower half of a stream emerging from an 75

opening 44 is therefore spread in a direction lengthwise of the roll by the plate 46 before the stream reaches the edge of the first bed plate bar. The upper half of a stream encounters the roll blades 26 sooner than the lower half and is consequently also spread laterally but by impact with the blades, so that by the time the upper half of a stream of stock reaches a point opposite the first bed plate bar it is spread laterally like the lower half.

It will be observed that the point at which the incoming stock strikes the beater roll is substantially at the first bed plate bar. This is important for the reason that as soon as a pocket 27 has been filled with stock, the high speed at which the roll rotates causes that stock to be thrown radially outward with a force substantially equal to the force with which the stock impinges on the roll blades. This is not objectionable where the stock strikes the roll blades substantially at the beginning of the bedplate bars, for it is desirable to have the stock forced radially outward toward the bedplate bars to aid disintegration.

Where, however, the nozzle structure directs the stream against the roll farther around the circumference at a point in advance of the bedplate bars, most of the gain due to the turbine effect is lost, because centrifugal force creates a tendency of movement of the stock in the pockets 27 in a radial direction, thereby producing pressure on the inside of the roll housing, thus offering a resistance against which the stock in the pockets must be moved circumferentially from the nozzle openings around to the bed plate.

The complete apparatus comprises a beater engine 10 as hereinbefore described, together with a storage and conveying trough 50 supported on columns 52 and a pump 54, the pump being operated by an electric motor 56 directly connected thereto and the beater by a second electric motor 58 drivably connected to the beater engine 10 by a silent chain 60. The pump 54 is supported on the lower floor 62 and the beater engine 10 on a base 64 on the upper floor 66.

The bottom of the trough 50 empties into the pump inlet housing 68. The large pipe 36 conveys the stock from the pump discharge housing 72 to the inlet housing 32 of the engine 10.

In proportioning the several elements of the apparatus shown, a stock single stage centrifugal pump of the required capacity and a suitable motor for driving it may first be selected. Such a pump and motor may move the stock through

the pipe 36 at about 250 feet per minute. A nozzle structure proportioned as shown will then raise this speed to approximately 2,000 feet per minute. The peripheral speed of the beater roll should then be kept at approximately 2,000 feet per minute.

Inasmuch as the turbine effect of the stock on the roll keeps the roll operating at this speed, the power required for rotating the roll will be only that necessary for performing the cutting and disintegrating function, and the motor 56 may consequently be selected having a revolution speed sufficient to produce the 2,000 feet per minute roll speed, and power sufficient only to cut and disintegrate the fibers of the stock.

The proportions above given are given by way of example only and are in no wise intended to impose a limitation on the scope of the structure. To more clearly define this structure, I claim:

1. In paper stock refining apparatus, the combination of a horizontal beater roll, a bedplate, a nozzle structure for directing separate streams of stock under high velocity tangentially against the blades at the edge of the bedplate, said nozzle structure comprising a large main nozzle portion the opening of which decreases in vertical dimension and increases in horizontal dimension as it approaches the roll, and a series of wedge shaped partitions in the large nozzle opening dividing said opening into a series of smaller nozzles tapering in both horizontal and vertical dimensions toward said roll.

2. The structure defined in claim 1 with a spreading plate extending the length of the roll, positioned to intercept the halves of the streams farthest from the roll, the one edge of the plate being adjacent the nozzle openings and out of the path of the streams and the other edge being adjacent the bedplate and substantially at the middle of the streams.

3. The structure defined in claim 1 with a spreading plate extending the length of the roll, positioned to intercept the halves of the streams farthest from the roll, the one edge of the plate being adjacent the nozzle openings and out of the path of the streams and the other being adjacent the bedplate and substantially at the middle of the streams, the transverse cross section of said plate being concave on the upper surface where it obstructs said streams.

WILLIAM V. KNOLL.
